UNITED STATES PATENT OFFICE.

CHARLES A. MORIN, OF BOSTON, MASSACHUSETTS.

INSOLE-TRIMMING MACHINE.

Application filed October 16, 1925. Serial No. 62,867.

In the production of shoes in accordance with the construction shown in my prior Patent No. 1,528,260, granted March 3, 1925, the insole is provided with a full feather, portions of which in the region of the shank and ball are subsequently removed so as to inset the edge face of the insole relative to the outer edge of the bottom face of the last. This brings the edge face of the insole at 10 these points definitely within the normal over-tread of the foot so that the inseam stitching along said unfeathered portions may be carried directly through the edge face of the insole. The normal foot contour, therefore, overhangs the inseam at 15 said unfeathered portions and is cradled on the lower margin of the upper, thus avoiding the formation of an uncomfortable stitch ridge on the inside of the insole. By 20 this construction, I obtain a smooth, level, flat foundation for the foot.

Heretofore I have removed the indicated portions of the feather by hand, but in order to overcome the disadvantages incidental to hand operation, I have devised a machine for trimming off the feather, either continuously around the insole, or at selected portions thereof. In such machine I have as far as practicable utilized existing 25 equipment, but I have so constructed and co-ordinated the several operating parts as to obtain a perfected result.

The construction and operation of my machine is fully described and illustrated in 30 the accompanying specification and drawings, and the characteristic features of novelty particularly pointed out in the appended claims.

In the drawings:

40 Fig. 1 is a fragmentary front elevation, partly in section, of a machine equipped in accordance with my invention.

Fig. 1^a is a fragmentary detail.

45 Figs. 2 and 3 are fragmentary end elevations illustrating successive operating positions of the machine.

Fig. 4 is a plan view of an insole from which the feather is about to be trimmed.

50 Fig. 5 is a similar view and showing the feather substantially wholly trimmed off, and

Figs. 6 and 7 are sections on the lines 6-6 and 7-7 respectively of Figs. 4 and 5.

55 As previously indicated, I utilize in so far as possible, standard equipment for inter-

mittently feeding the insole past the trimming knife which trims off the insole feather. For this purpose, I find the four motion work feed of the Singer stitching machine generally used in the shoe trade satisfactory, and in these drawings I have shown so much of such a machine as is necessary to an understanding of my invention.

60 In such a machine, the work table is indicated at 1 and the head at 2 thereof. Reciprocable vertically in suitable guides carried by said head is a cutting blade 3. The fully-feathered insole 4 is positioned at an angle to the plane of reciprocation of the knife 3 with its feather 5 extending beyond such plane for removal by the knife. As here 65 shown, I mount on the work table 1 an inclined block 6 (Fig. 1^a) which is vertically slotted at 7 and 8. At one side of the block 70 6 is fixed an upwardly inclined supporting plate 9 on which the insole is adapted to rest in somewhat overhanging relation to said block. At the other side of said block I mount a guide finger 10, the free end of 75 which extends over the block and constitutes a marginal edge guide for the insole.

The insole is intermittently fed past the trimming knife by means of a feed plate 11 which is disposed beneath the insole and works in an elongated slot 11' in the work 80 table. The feed plate has a four motion feed; that is, it is first raised up against the under face of the insole, next moved forwardly a slight distance to feed the insole past the trimming knife, then lowered to 85 release the insole and finally moved rearwardly back to its original position in order to repeat the cycle.

This motion may be imparted to the feed plate by the standard four motion feed of 90 the Singer machine which in general may be said to include a rocker lever 14 carrying the feed plate and adapted to be raised and lowered by means of a link 15 driven from the drive shaft of the machine and a pair 95 of eccentrics 17 operated by a link 18 driven from the drive shaft of the machine and operatively connected to the rocker 14.

The upper end of the said feed plate is 100 serrated as indicated at 19, whereby to effectively engage the under face of the insole and said feed plate reciprocates in the slot 8 of block 6, the knife 3 reciprocating in slot 7 of said block.

105 Light overhead bearing is maintained on 110

the upper face of the insole by means of a beveled wheel 20 which is loosely mounted on a hanger 21 carried by the head of the machine.

In operation, the insole 4 is positioned upon the block 6 with its feather 5 projecting into the path of travel of the knife 3, and with its marginal edge above the feather 5 in abutment against the free end of the guide 10. When the machine is started, the knife continuously trims off the projecting feather as the feed plate 11, traverses the insole therepast.

10 The trimming cut is made at an angle to the body of the insole, as indicated at 22, Fig. 7, this bevel cut being of advantage in the particular type of insole and shoe involved herein in that it permits the inseam stitching to be further inset from the edge face of the last bottom.

15 Various other modifications in the form and construction of my invention may obviously be made within the spirit and scope 20 of my invention as defined by the appended claims.

What I therefore claim and desire to secure by Letters Patent is:

25 1. In a machine for trimming the feather from an insole, a reciprocable cutter, a work 30 support at one side of the cutter adapted to position the insole at an angle to said cutter with its feather projecting past the plane of travel of the cutter, a guide at the opposite side of said cutter and against which 35 the edge face of the insole above said feather is adapted to be abutted, and a work feeder for feeding the insole past said cutter.

40 2. In a machine for trimming the feather from an insole, a reciprocable cutter, a work 45 support at one side of the cutter adapted to position the insole at an angle to said cutter with its feather projecting past the plane of travel of the cutter, a guide at the opposite side of said cutter and against which 50 the edge face of the insole above said feather is adapted to be abutted, means for maintaining overhead bearing upon the insole

while positioned upon said support, and a work feeder for feeding the insole past said cutter.

3. In a machine for trimming the feather from an insole, a cutter and a feeder, and an inclined work support adapted to position the insole at an angle to the cutter with its feather projecting beyond the plane of travel of the cutter, said work support having a pair of spaced parallel vertical slots through which the cutter and feeder respectively reciprocate.

4. In a machine for trimming the feather from an insole, a cutter and a feeder, and an inclined work support adapted to position the insole at an angle to the cutter with its feather projecting beyond the plane of travel of the cutter, said work support having a pair of spaced parallel vertical slots through which the cutter and feeder respectively reciprocate, and a guide against which the edge face of the insole above said feather is adapted to be abutted.

5. In a machine for trimming the feather from an insole, a reciprocable cutter, an inclined plate at one side of the cutter on which an insole is adapted to rest with its feather projecting into the path of reciprocation of the cutter, and an inclined guide at the opposite side of the cutter against which the edge face of the insole above said feather is adapted to be abutted.

6. In a machine for trimming the feather from an insole, a reciprocable cutter, an inclined plate at one side of the cutter on which an insole is adapted to rest with its feather projecting into the path of reciprocation of the cutter, an inclined guide at the opposite side of the cutter against which the edge face of the insole above said feather is adapted to be abutted, and an inclined block disposed between said plate and guide and slotted to permit the passage therethrough of said cutter.

In testimony whereof I affix my signature.

CHARLES A. MORIN.
